(57) **CLAIM**

The ornamental design for a skin abrasion tool as shown and described.

DESCRIPTION

FIG. 1 is a first perspective view of a skin abrasion tool of the present invention;

FIG. 2 is a second perspective view of the invention shown in FIG. 1;

FIG. 3 is a top elevational view of the invention shown in FIG. 1;

FIG. 4 is a bottom elevational view of the invention shown in FIG. 1;

FIG. 5 is a first side elevational view of the invention shown in FIG. 1;

FIG. 6 is a second side elevational view of the invention shown in FIG. 1;

FIG. 7 is an enlarged elevational view of a first end of the invention in FIG. 1; and,

FIG. 8 is an enlarged elevational view of a second end of the invention shown in FIG. 1.
